ATTORNEY.

UNITED STATES PATENT OFFICE.

BENJAMIN F. TOBIN, JR., OF DETROIT, MICHIGAN, ASSIGNOR TO CONTINENTAL MOTORS CORPORATION, OF DETROIT, MICHIGAN, A CORPORATION OF VIRGINIA.

SHIPPING CRATE.

Application filed February 24, 1920. Serial No. 360,894.

To all whom it may concern:

Be it known that I, BENJAMIN F. TOBIN, Jr., a citizen of the United States, residing at Detroit, in the county of Wayne and 5 State of Michigan, have invented a new and useful Improvement in Shipping Crates, of which the following is a specification.

My invention relates to an improved form of shipping crate designed particularly for 10 shipping internal combustion motors or similar articles having irregular or curved bottom portions requiring protection, and further requiring side or end support for the articles when shipped by freight, particularly when the articles are relatively 15 heavy as is the case with the motors referred to. By my invention I provide a simple, strong and effective construction for this purpose made preferably from iron or steel 20 bars provided with attachment devices by which the crate may be readily adapted to support different styles of articles of the same class; for example different models of motors of the kind referred to, and by my 25 construction, I also provide for collapsing the crate when it is to be returned to the factory after having been used in the manner referred to.

My invention will best be understood by 30 reference to the accompanying drawings showing a preferred embodiment thereof in which

Fig. 1 is a perspective view of my improved crate in condition for shipping, and 35 Fig. 2 is a side view of the crate shown in Fig. 1 in collapsed condition.

Similar numerals refer to similar parts throughout the several views.

As shown in Fig. 1, my improved crate 40 consists of a base 10 made preferably of an iron or steel bar bent in the form of a rectangle and having its end portions secured together preferably by welding. I prefer to construct the skeleton base referred to from 45 an angle bar, as a bar of such cross section is stiff, light and well adapted to co-operate with the other parts of the device. The upper portion of the crate consists of a frame 11 similar to the base 10 and made preferably 50 in the same manner and from an angle bar, the only difference being that while the legs of the angle bar forming the base project

outwardly and upwardly, the legs of the angle bar forming the frame 11 projecting outwardly and downwardly, and furthermore one end of the frame 11 is depressed as indicated at 12 to form a saddle for receiving a cylindrical part of the motor or other device to be shipped in the crate. The base 10 and the frame 11 are connected together and the frame is supported from the base by means of supporting legs 13, 14 and 55 15, 16, made preferably from flat bar iron or steel. The legs 13 and 14 are rigidly connected together by a transverse brace 17, 60 and the legs 15 and 16 are similarly connected together by a brace 18. Each of the supporting legs is provided at each end with outwardly extending lugs the outer edge 65 surface of which rests against the inner 70 faces of the horizontally extending legs of the angle bars forming the base and frame when the crate is in position for use. The supporting legs 13 and 14 are pivotally connected with the vertically extending leg of 75 the angle bar of the base, by the bolts 19 extending through the lugs which are near the adjacent end of the base, and the supporting legs 15 and 16 are similarly connected to the base by bolts 20 extending 80 through the lower lugs of the supporting legs which are further from the adjacent end of the base. The supporting legs 13 and 14 are pivotally connected with the frame 11 by bolts 21 extending through the 85 downwardly projecting leg of the angle bar forming said frame and through the upper lugs of the supporting legs which are further from the adjacent end of the frame and the upper ends of the supporting legs 15 and 16 are similarly connected to the frame by 90 bolts 22 extending through the lugs on the upper end of the legs 15 and 16 which are nearer the adjacent end of the frame 11. The crate is held in its operative position 95 by braces 23 extending diagonally of the crate between the bolts 20 and 21 in which position the ends of the supporting legs are held firmly against the inner surfaces of the horizontally extending legs of the angle bars 100 forming the base and frame. When it is desired to collapse the crate to the position indicated in Fig. 2, the nuts may be removed from the bolts 21, the ends of the braces 23

slipped from the bolts 21, the nuts replaced on the bolts 21 and the supporting legs rotated on their pivotal connections thus bringing the frame 11 adjacent the base 10 5 in much the manner that the members of a parallel ruler may be moved towards each other.

The shipping crate shown in the drawings is adapted particularly for use in shipping internal combustion motors, and as is well known, devices of this kind have a cylindrical portion on one end which may be employed as a supporting portion, and this portion may when the crate is constructed 10 15 of the proper size, rest in the saddle 12 where it is secured by a clamping plate 24 by suitable bolts. A second saddle bar 25 is provided on the frame 11 for supporting other motors of different size and brackets 20 26 are also secured to the frame 11 at the same end as the saddle bar 25 to support other motors not provided with a convenient cylindrical end support. At the other end of the frame, the motor may be secured thereto by suitable bolts extending through holes 27 formed in the frame, or for other sizes corresponding retaining bolts 25 30 may pass through brackets 28 rigidly secured to the frame.

30 By providing the frame 11 with sets of brackets to meet the needs of different styles of such motors for shipping purposes, it will be observed that the same crate may be used for shipping a motor of 35 any desired style without interfering with the use of the crate subsequently for shipping motors of other styles or models. It will at once appear that crates of the kind under consideration must be substantial 40 and strong, and furthermore that they must occupy a minimum of space when being returned to the manufacturer who has used them in shipping his goods. All of these 45 considerations are realized by my improved construction.

While I have shown my invention in the particular embodiment above described, I do not, however, limit myself to this exact construction in carrying out my invention, as I may employ equivalents thereof known to the art at the time of the filing 50 of this application without departing from the scope of the appended claims.

What I claim is:

55 1. In a device of the class described, the combination of a base, a frame, legs for supporting said frame above said base, said frame adapted to support articles for shipping, braces for holding said legs in supporting position, and fastening devices 60 readily removable from said braces, said legs being pivotally connected at their ends to said base and frame to permit collapsing said frame against said base, and said legs 65 having transverse and oppositely extending

lugs at their ends engaging corresponding surfaces on said base and frame to hold said legs in supporting position.

2. In a device of the class described, the combination of a base, a frame, legs for supporting said frame above said base, said frame adapted to support articles for shipping, braces for holding said legs in supporting position, and fastening devices readily removable from said braces, said legs being pivotally connected at their ends to said base and frame to permit collapsing said frame against said base, said frame carrying a plurality of devices for attachment to articles of different size to be shipped.

3. In a device of the class described, the combination of a base, a frame, legs for supporting said frame above said base, said frame adapted to support articles for shipping, braces for holding said legs in supporting position, and fastening devices readily removable from said braces, said legs being pivotally connected at their ends to said base and frame to permit collapsing said frame against said base, and said legs having transverse and oppositely extending lugs at their ends engaging corresponding surfaces on said base and frame to hold said legs in supporting position, said braces 95 extending diagonally between the ends of said legs and secured to the pivotal connections thereof.

4. In a device of the class described, the combination of a skeleton base comprising an angle bar bent and its ends secured together to form a rectangle, the legs of said angle bar extending horizontally and vertically of the base, a similarly formed frame, the vertical legs of the angle bars of said brace and frame extending towards each other, supporting legs pivotally connected to said vertical legs, and brace bars extending diagonally between the pivotal connections of said supporting legs to hold the latter 100 substantially perpendicular to said base and frame, the connections at one end of the braces being readily separable to permit collapsing the frame against the base, said supporting legs have oppositely disposed 105 transverse end lugs engaging the inner surfaces of the horizontal legs of said base and frame bars in supporting position.

5. In a device of the class described, the combination of a skeleton base comprising 110 an angle bar bent and its ends secured together to form a rectangle, the legs of said angle bar extending horizontally and vertically of the base, a similarly formed frame, the vertical legs of the angle bars 115 of said base and frame extending towards each other, supporting legs pivotally connected to said vertical legs, and brace bars extending diagonally between the pivotal connections of said supporting legs to hold 120 125 130

the latter substantially perpendicular to said base and frame, the connections at one end of the braces being readily separable to permit collapsing the frame against the 5 base, said supporting legs have oppositely disposed transverse end lugs engaging the inner surfaces of the horizontal legs of said

base and frame bars in supporting position, and brackets carried by said frame for securing thereto articles to be shipped. 10

In witness whereof, I hereunto subscribe my name this 17th day of February, A. D. 1920.

BENJAMIN F. TOBIN, JR.
